UNITED STATES PATENT OFFICE.

ROLAND C. HILTON, OF TROY, NEW YORK, ASSIGNOR, BY DIRECT AND MESNE ASSIGNMENTS, TO REECE-HILTON INC., OF TROY, NEW YORK, A CORPORATION OF NEW YORK.

TIRE-PUMP.

1,375,843.

Specification of Letters Patent. Patented Apr. 26, 1921.

Application filed March 12, 1919. Serial No. 282,137.

To all whom it may concern:

Be it known that I, ROLAND C. HILTON, a citizen of the United States, residing at Troy, county of Rensselaer, State of New York, have invented an Improvement in 5 Tire-Pumps, of which the following description, in connection with the accompanying drawing, is a specification, like characters on the drawing representing like parts.

10 This invention relates to tire pumps for pumping up automobile tires and has for its object to provide a novel pump of this nature which can be readily clamped to the running board and which has various improved features, all as will be more fully 15 hereinafter set forth.

In order to give an understanding of my invention, I have illustrated in the drawings a selected embodiment thereof which will 20 now be described, after which the novel features will be pointed out in the appended claims.

In the drawings, Figure 1 is a side view with a part broken out of a pump embodying my invention;

Fig. 2 is a top plan view;

Fig. 3 is a section on the line 3—3, Fig. 1;

Fig. 4 is a reduced view of the pump;

Fig. 5 is a section on the line 5—5, Fig. 1;

30 Fig. 6 is a side view of the joint between the sections of the handle;

Fig. 7, is a section on the line 7—7, Fig. 3.

The pump casing comprises a cylinder 1 and two head or end members 2 and 3 between which the cylinder is situated. The cylinder 1 may conveniently be made from a piece of tubing and it is shown as clamped between the heads or end members 2 and 3 by means of tie rods 4. Each head or end member is provided with a foot 5 adapted to rest on the running board 30, and each foot has a clamp 6 associated therewith by which it may be clamped to the running board. These clamps are preferably hinged 40 to the feet, each clamp having the arm 7 which is pivotally mounted in the flange portion 8 of the foot, and the arm 28 which extends under the running board and carries the usual clamping screw 9. By pivotally connecting the clamps to the feet, said clamps can be folded up against the cylinder when the pump is not in use.

Situated within the cylinder is a piston 10 which will preferably be of the usual cup 55 washer type. This piston is carried by a

piston rod 11 which projects through the head or end 3. 12 indicates an operating lever which is pivotally connected to the projecting end of the piston rod, as shown at 13. The lower end of the operating lever 60 is pivotally connected at 14 to a pair of link members 15 that are pivotally connected to the head 2 at 16, said link members being situated on either side of the cylinder. The head or end 3 is provided with an air inlet opening 17 and the head or end 2 is provided with a valved connection 18 to which a discharge pipe 19 is secured. This valved connection 18 is provided with an outwardly-opening check valve 20 adapted 65 to seat against a valve seat 21.

With the above-described construction a vibrating movement of the lever 12 will operate to vibrate the piston 10 in the cylinder 1, and during each stroke of the piston to 75 the right air will be drawn past the piston into the left-hand end of the cylinder, and during the stroke of the piston to the left, this air will be forced through the discharge valve into the discharge pipe 19. 80 The links 15 serve as a fulcrum to which the lever 12 is pivoted and because they are pivoted to the pump casing they also allow for the vertical movement of the lower end of the lever, thus preventing any binding of 85 the parts.

The lever 12 is so shaped that when it is depressed into the dotted line position, Fig. 1, thereby to force the piston to the extreme limit of its compression stroke, the pivot 14 90 comes substantially into alinement with the piston rod 11. The lever connection, therefore, constitutes a toggle device which is straightened when the piston is at the end of its compression stroke, and hence the 95 greatest power is developed at this point. In operating the pump, the resistance which the compression of the air offers to the piston is the greatest as the piston nears the end of its compression stroke and my arrangement, therefore, has the advantage that the greatest power will be developed at the point in the stroke where the greatest resistance is offered to the movement of the piston.

I have herein illustrated the lever 12 as provided with an extension 22 thereby to afford a better leverage. This extension 22 is movably secured to the lever so that it can be folded back into the dotted line po- 100 105 110

sition Fig. 4 when the pump is to be stored. To provide for this movable or adjustable connection between the lever and the lever extension, I have made the lever with the 5 transversely-extending groove 23 at its outer end in which groove is received a rib 24 formed on the inner end of the extension 22. The meeting ends of the lever 12 and extension 22 are clamped together by means of 10 a clamping bolt 25, said bolt holding the rib 24 in the groove 23. By partially unscrewing the nut 26 on the clamping bolt, the extension 22 may be folded back against the lever 12, thus reducing considerably the 15 space required for storing the pump.

It will be noted that the pump casing is clamped firmly to the running board 30 and, therefore, the cylinder of the pump is held rigidly in position during the pumping operation.

I claim:

1. In a pump, the combination with a pump casing comprising a cylinder element

and two heads or end members between which the cylinder is clamped, each end member having a foot to rest on a support, of a clamp pivotally connected to each foot and by which said pump casing may be clamped to said support, each clamp being pivoted to swing about an axis extending 25 transversely to the cylinder, a piston operating in said cylinder, and means to actuate said piston.

2. In a pump, the combination with a pump casing comprising a cylinder element 30 and two heads or end members, a clamp pivotally connected to each end member to swing about an axis transversely to the cylinder, each clamp being of a size to permit it to be swung against the cylinder between 35 the end members, a piston in said cylinder, and means to actuate it.

In testimony whereof, I have signed my name to this specification.

ROLAND C. HILTON.
